US0D1043190S

(12) United States Design Patent (10) Patent No.: US D1,043,190 S
(45) Date of Patent: * Sep. 24, 2024

(54) MULTI-FUNCTION DESK

(71) Applicant: Hongbing Zheng, Hangzhou (CN)

(72) Inventor: Hongbing Zheng, Hangzhou (CN)

() Term: 15 Years

(21) Appl. No.: 29/826,298

(22) Filed: Feb. 11, 2022

(30) Foreign Application Priority Data

Jan. 17, 2022 (CN) 202230028161.7

(51) LOC (14) Cl. 06-03

(52) U.S. Cl.

USPC D6/648

(58) Field of Classification Search

USPC D6/329, 641, 648, 648.1, 648.2, 648.4, D6/649, 651, 651.1, 652, 652.1, 653, D6/653.1, 653.14, 653.18, 653.21, 653.22, D6/653.23, 654, 654.18, 654.21, 654.23, D6/655, 655.1, 655.11, 655.14, 655.16, D6/655.18, 655.21, 655.22, 655.23, 656, D6/656.16, 656.17, 656.18, 656.19, 685, D6/695, 695.1, 695.3, 695.4, 702

CPC A47B 17/033; A47B 21/00; A47B 21/06; A47B 83/001
